[57] CLAIM

The ornamental design for a pendulum for a clock, as shown and described.

DESCRIPTION

FIG. 1 is a front elevational view of a pendulum for a clock showing my new design, the rear being the same in appearance as the front;

FIG. 2 is a right side elevational view thereof, the left side being the same in appearance as the right side;

FIG. 3 is a top plan view thereof;

FIG. 4 is a bottom plan view thereof; and

FIG. 5 is a front elevational view thereof on a reduced scale with the upper portions omitted for ease of illustration, the broken line showing of a clock being environment only and forming no part of the claimed design.

FIG. 1

FIG. 2

FIG. 3

FIG. 4

FIG. 5
